KEYBOARD TAPE PERFORATOR

Irving Naxon, Chicago, Ill.

Application June 3, 1947, Serial No. 752,124

11 Claims. (Cl. 164—113)

1

My invention relates to tapes on which letters, symbols or other characters are recorded, and more particularly to means for imposing the same; and one object is to provide a machine which imposes such letters, symbols or characters in the form of perforation groups representative of the same.

A further object is to provide means actuated by the operation of a standard typewriter keyboard to procure the formation of desired perforation groups in the form of ordinary reading matter, or in code-groups representative of the symbols.

Another object is to employ simple mechanical means, in conjunction with an electrical solenoid unit, to perforate the tape, space the characters, and control the spacing for characters of different widths.

An important object is to construct the machine along lines of compactness and with a simple and efficient arrangement of parts.

With the above objects in view and any others which may suggest themselves from the description to follow, a better understanding of the invention may be had by reference to the accompanying drawings, in which—

Fig. 1 is a schematic perspective view of a sign showing the application of the instant machine;

Fig. 2 is a front elevation of the machine, with a frontal cover plate broken away;

Fig. 3 is a section substantially on the line 3—3 of Fig. 2;

Fig. 4 is a detail section on the line 4—4 of Fig. 3;

Fig. 5 is a fragmental enlargement of a punch assembly showing in the right-hand upper corner of Fig. 3;

Fig. 6 is a top plan view of the upper portion of the machine;

Fig. 7 is a perspective view, taken from the rear of the machine, of a spacing control;

Fig. 8 is a detail section on the line 8—8 of Fig. 7;

Fig. 9 is a diagrammatic view of the electrical circuit for the solenoid unit;

Fig. 10 is a section similar to Fig. 3 showing a modification and broken away intermediately;

Fig. 11 is a section on the line 11—11 of Fig. 10, partly broken away; and

Fig. 12 is a detail perspective view of a lever shown horizontally in the center of Fig. 11.

Referring specifically to the drawings, 15 denotes the base of the machine, the same being a casting with a marginal skirt 16 and supporting feet 17. The interior of the base is mainly oc-

2

cupied by a group of levers 18 leading forward to the keys 19 of a standard typewriter keyboard; and the levers 20 of the conventional spacing bar 21 occur below the levers 18.

5 The base 15 receives a massive angle bar 22 across the top for the support of an upstanding frame plate 23. The latter is drilled with a circular row of holes 24 in which the forward portions of a series of horizontal pins 25 are slidably disposed. The rear ends of the pins abut a backing plate 26 secured by bolts 27 to studs 27a projecting rearwardly from the frame plate; and reductions 28 of such rear ends extend freely through the backing plate to receive terminal rods 31c are directed from the extensions 30 into the sockets 29 of the pins 25, these being chosen with a predetermined relation to the letters, numbers and characters represented by the keys 19. Thus, the depression of any one of these secures the advance of the corresponding pin 25 through the frame plate 23, the socket 29 forming a limit for such advance when it meets the backing plate 26. The staggering of the pins permits them to be made of a relatively large diameter without being too closely spaced. Figs. 15 and 4 show that a comb 31 formed with frontal slots 31a is designed as a separating guide for the extensions 30, and is supported at the ends by posts 31b.

30 The pins 25 are designed to form stops for a selector disc 32 which is located a short distance in front of the frame plate 23. The disc is reduced to four spider arms 33 on the inside; and these carry a hub 34 which is secured by a set-screw 35 to the forward end portion of a tube 36 extending axially of the disc and the circle of pins 25. The disc is designed to rotate in a clockwise direction according to Fig. 2; and to prevent the reverse rotation of the disc one of its arms 33 carries a pawl 37 kept in contact with a stationary ratchet wheel 38 by a spring 39 extending from the pawl to an adjacent spider arm 33, the ratchet wheel 38 being made fast to the frame plate 23.

35 The drive for the selector disc 32 originates with an electric motor 40 carried by a frame 41 whose base 42 is bolted at 42a on the rear portion of the machine base 15. As indicated in Figs. 3 and 6, a speed-reducing drive is taken from the motor shaft 43 by meshing a pinion 44 on the same with a gear 45 carried by a jack

shaft 46; and the latter transmits the drive to a gear 47 whose hub 48 is freely rotatable on the axial tube 36. The rear end portion of the latter is journaled in a bushing 49 carried by the frame 41; and the tube receives the hub 50 of a disc 51 in opposed relation to the gear 47, such hub being made fast by a set-screw 52. The disc 51 carries a yieldable facing 53 in frictional engagement with the gear 47. Fig. 3 shows that the gear is urged against the facing 53 by a spring 54 backed by a block 55 made fast on the tube 36 by a set-screw 56. Thus, the motor drive is transmitted to the center tube 36 by way of a yieldable clutch, and may continue or slip without damage to the tube in case the latter meets some resistance or impediment during its rotation.

The selector disc 32 is designed to be in constant rotation until a key 19 is depressed, when the resulting projection of the corresponding pin 25 presents an impediment to a block or yieldable stop 57 forming the outer end of an arm 58 pivoted at 59 to one of the spider arms 33. It is noted that the receiving face of the block has a pair of depressions 60 abreast to meet either row of the staggered pins 25. The block recedes a short distance in this event, and backs against the advancing edge of the related spider arm 33 as a stop, the arm of the block drawing on a spring 61 extended from an adjoining spider arm in this event.

The action of the affected pin 25 in respect to the receding block 57 precedes the positive stopping of the selector disc 32 when the same advances through the leeway afforded by the recession of the block 57. This indicates that the disc has a predetermined stopping point for each key 19, such factor being utilized to locate a corresponding character index in registration with a die, with which a punch is operative on the tape to perforate the same with the character index.

The action just mentioned is initiated by the closing of a switch in a solenoid circuit. The switch is composed of a pair of spring blades 62 and 63 which are carried at one of their ends by an insulation block 64 and are normally spaced at their other ends. The block has a base 65 attached by screws 66 to a spider arm 33; and the blade 62 is in the path of an insulation button 67 carried by the pivoted arm. The recession of the block 57 therefore serves to close the switch. Figs. 3 and 6 show that the solenoid 68 energized by the closing of the switch is carried by a base 69, which is secured in spaced relation to the frame plate 23 by bolts 70. The armature of the solenoid is indicated at 71, the same carrying a plunger 72 whose advance is resisted by a compression spring 73 carried by the plunger between the base 69 and the armature 71.

Since the solenoid switch is carried by the rotary disc 32, an adaptable current connection must be provided. The tube 36 furnishes a central path for the wires (not shown) leading to the switch, but the origin of these is in the form of a plate 75 secured by screws 76 to the frame 41. Screws 77 permit wires from a suitable current supply source to be attached to the plate 75; and the latter carries a pair of spring brushes 78 in contact with concentric rings 79 mounted on the face of a disc 80. The latter is formed with a hub which is fast on the rear end portion of the tube 36; and the rings 79 carry binding posts 81 from which the wires for the solenoid switch may be led by way of side openings 82 into the tube. The connection of the switch wires is thus

maintained while the tube is in rotation. Incidentally, the tube is designed to receive a short forward thrust at times, and it is noted that the bushing 49 extends a short distance to the rear from its support 42 in order to allow the necessary forward movement.

The selector disc 32 is representative of the letters of the alphabet, and the outer portion of the disc is formed with perforation groups 85 symbolical of each letter. Each group is based on the scheme that a letter of full width requires seven perforations in height and five in width, the horizontal and vertical rows of which fall into registration with corresponding holes in the various groups 85, each group of which comprises a predetermined character. Fig. 1 shows a perforation-word made up of full-width letters. It follows, therefore, that letters of less than full width—or characters of less than full height—use only a portion of the perforations in the group. Thus, the letter "I" would only employ a single column of perforations. Recalling that the selector disc is geared for continuous rotation, and that the disc can be stopped at any desired point by the pressing of the proper key 19, the stopping point is designed to locate the corresponding perforation group 85 at the top of the disc 32. Here the frame plate 23 is formed with an overhanging casting 86 in which a box or die-block 87 is fitted, screws 88 serving to attach the box from the rear.

The rear wall 89 of the box 87 serves as a bearing for a group of pin-punches 90. The punches have slight rearward reductions 92 passing through a backing plate 91, as shown in Fig. 5. The punches are also slightly shouldered within the box to receive a stripper-plate 93; and they terminate in an inner punch-guide 94. An outer companion female guide 95 is spaced from the inner one by a pair of parallel spacing shims 96; and screws 97 secure the dies to the block.

Disposed as described, the punches 90 may be given a short forward movement, causing them to advance through the space between the dies 94 and 95 into the latter die. The spacing of the dies is such as to permit the passage of a paper tape 100 through the said space, the advance of the punches serving to perforate the tape. Since it is intended to punch the tape with perforations forming a desired letter or character, the selector disc 32, with the corresponding perforation-group stopped in topmost position as mentioned, is employed as a pattern for indexing the characters. The short forward movement of the selector disc 32—previously referred to—is designed to push the punches forward, and it will be apparent that only the punches for the desired letter or character will be affected by the advance of the disc, the balance of the punches finding clearance in the disc perforations with their reduced rear ends 92. Obviously, when the spacing bar 21 is struck, no perforations are to be made in the tape. Fig. 3 shows that the levers 20 of this bar are adapted to pull down on a link 21a and rock an angle lever 21b to project a pin 21c through the frame plate 23 into the path of the stop block 57. It is understood that the corresponding stop of the selector disc 32 will present to the punch group a character area full of openings, so that the punch group is not actuated by the advance of the selector disc.

It will be recalled that the stopping of the character-carrying element, or selector disc 32 at any point in its rotation served to close the solenoid switch 62—63. As noted in Fig. 3, the

solenoïd-activated rod 72 is reduced at its forward end with a round-tipped pin 105 on which is tightly mounted a hammer 106. Thus, the latter imparts the aforesaid forward movement to the selector disc, while the pin 105 insures accurate registry of the perforation-group with the punches by passing through an opening 107 in the disc and into a hole 108 in the backing-plate 91. Fig. 2 shows that an opening 107 is provided for each perforation-group. The bullet-shaped end 105, in passing through a given hole 107 and into the hole 108 in the die-block leads the hammer 106 by a short distance so that any slight rotational error is not only corrected before the hammer presses the disc against the backs of the punches, but also assures that the disc is positively locked against rotational movement during the perforation-cycle. Moreover, I prefer to effect this correction by relating a given index hole 107 with respect to its elemental character-area in such a manner that the entry of the correction finger 105 causes a slight backward rotation of the disc. This backward movement, however, is not sufficient to open the contact points, since the springs supporting the latter are designed to effect a wiping action accompanied by a considerable "follow" of the points, the final opening of the contacts being effected instantly upon the manual release of a finger key, which in turn withdraws the pin 25 rearwardly and out of registration with the stop 57 and immediately permits, concurrently with resumption of rotation of the disc, the spring 39 to open the contacts.

A spring-backed pin 109a slideable in the plates 23 and 26 is effective against a disc 109b secured by a set screw 109c on the tube 36 to back the selector disc 32 away from the punch group; and the retraction of the latter is insured by a pair of stripper-springs 110 which are tied with their forward ends to the stripper plate 93 and with their rear ends to the backing plate 91, as seen in Fig. 6. It will also be observed that the momentary stoppage of the center tube 36 is not prejudicial to its drive from the geared disc 47, since the latter will simply slip along the yieldable disc 53 during such stoppage, resuming the driving of the tubular shaft the moment the selector disc is freed of the punches and registry pin.

The tape 100 extends forwardly from a spool 190 at the rear of the machine, takes an inward turn past a hanger 111, and enters a frontal channel guide 112. It then passes between the die-plates 94-95 as previously described, and continues in a second channel guide 113. A mechanism is provided to feed the tape in the direction indicated by the arrow in the bottom right-hand portion of Fig. 6, the feed taking a stroke after each perforating operation. The mechanism originates with a transversely positioned arm 115 having one end pivoted as indicated at 116 to a bracket 117. At a point over the rod 72 the arm receives an angle plate 118 from below, screws 119 securing the same to the arm. The skirt of the angle plate is directly behind a pin 120 extending rearwardly from the hammer 106. A draw-spring 123 extends between the angle plate and a screw 122, so that the arm 115 swings forward yieldably on the advance of the hammer, through the medium of spring 123. The rear-most position of the arm 115 is controlled by nuts 123a which are adjustable on a screw 123b projecting rearwardly from the frame plate 23. A link 124 is pivoted with one end as indicated

at 125 to the free end portion of the arm 115, extending forwardly to pivot at 126 with one end of an angle lever 127. The latter is medially centered for rotation on a post 128 which is fixedly supported vertically from the horizontal part of an L-bracket 131f carried by the frame plate 23, a ratchet wheel 129 also being rotatably mounted on the post 128. The other end of the angle lever 127 carries a pawl 130 drawn to the ratchet wheel by a spring 131. Thus, when the arm 115 swings forwardly during a perforation-cycle the pawl slips the ratchet teeth, but operates the ratchet wheel on the return stroke. A suitable detent 131a, adjustably pivoted at 131b, is drawn by a spring 131c for engagement with the periphery of the ratchet wheel; and the tension of the spring is made variable by a bracket 131d adjustable by means of a screw 131e along the frontal L-bracket 131f. The ratchet wheel is carried by a sprocket wheel 132, whose frontal teeth pass through an opening 133 in the channel guide 113 and mesh with a medial series 134 of perforations made in the tape, so that the latter is fed the width of a perforation group 85 each time the punches recede. In the present form this group comprises the equivalent of five vertical rows of holes (consequently five feed holes) plus an additional feed hole, or a total of six feed holes; the sixth feed hole serving to space the letters apart. A press bar 135 holds the tape in mesh, being carried by rods 136 extending from a pin 137 pivoted in the wings of the channel guide 113. The pin is urged by a torsion spring 138 to apply the press bar.

While the feed just described moves the tape 100 the width of a regular perforation group 85 (plus one feed-hole), a shorter feed stroke is necessary where a narrow group occurs, such as for the letter "I," a semi-colon, or a different character of the same width. A mechanism to induce a corresponding feed stroke is illustrated in Figs. 3, 6 and 7. Thus, the type bars representing the narrow perforation groups are indicated at 140, and a series of lugs 141 rising from a comb 142 are in the depression path of the said type bars. The other end of the plate 142 is wrapped around and made fast to a crossrod 143 journaled in the sides of the base 16 as indicated at 144. The rod 143 is extended rearwardly with a short arm 145, to the outer end of which is linked an upwardly-extending link 146. The upper end of the latter is linked to one end of a lever 147 which is medially pivoted at 148 to the back of the frame plate 23. The other end of the lever 147 carries a rearwardly extending lug 149, which terminates with a lip 150. The lug 149 is in front of a wing 151 forming the free end of the pivoted arm 115. A spring 152 from a fixed point draws downwardly on the outer end of the lever 147 and thus keeps the lug 149 at a height suitable for clearance by the wing 151 when the latter assumes the idle stroke after each tape feed. However, when any one of the type bars 140 is depressed, the cross-rod 143 is caused to turn with the effect of swinging the lever 147 in a counter-clockwise direction as seen in Fig. 7. This action lowers the lug 149, and the wing 151 therefore advances over the lip 150 and meets the rear end of the lug on the stroke referred to. Now the link 124 cannot follow the full forward stroke of the hammer 106 and therefore causes the pawl 130 to slip less teeth of the ratchet 129. Therefore, on the return of the link 124 the ratchet turns a lesser distance, and the next

feeding stroke of the tape is correspondingly shortened.

Figs. 10, 11 and 12 show a modification of my invention. To reduce weight, the selector disc 32 is now made lighter and supplemented by a cluster of flexible segments 160 secured to the disc by screws 161. Behind the disc is a lever 162 having one end pivoted to the disc as shown at 163 while the other end is formed with concavities 164 corresponding to the depressions 60 made in the block 51 forming part of the main control, such concavities lending the lever 162 the same function in respect to the pins 25 as that of the block. However, the backing action of the lever 162 is transmitted outwardly to one wing 165 of an angle lever 166 pivoted at 167 in a frontal frame 168 carried by the disc 32. The other wing of the angle lever then swings rearwardly against a rod 169 slidable in the center tube 36. The solenoid switch 62-63 is now extended from a bracket 170 carried on the rear side of the motor frame 42. The rear end of the rod 169 carries an insulation tip 171 in touch with the switch arm 62, and it is apparent that the backing action of the rod will close 25 the switch.

In the modification, the forward action of the hammer 106 against the character-carrying segments 160 flexes the latter slightly forward, thereby obviating the necessity of shifting the entire wheel forward as is necessary with the wheel shown in Fig. 2, heretofore described. Moreover, since the motion necessary to close the pair of contacts 62-63 is now transmitted mechanically through the action of the bell crank lever 165-166, the modification makes it possible to keep the said contacts off the wheel, therefore obviating the necessity of the brushes and slip rings 78 and 79, shown in Fig. 9, for use in connection with the solid character-carrying 40 wheel.

Fig. 1 is a schematic illustration of the applicability of the perforator for electric sign operation. Thus, the sign is indicated at 180. The perforated tape 100 issuing from the perforator 181 is first led through a stop mechanism 182, and then through a transmitter 183. The current from the transmitter is relayed through a cable 184 to a sign controller 185, and a final cable 186 extended from the latter to the sign. The technique employed here is fully illustrated in the Nachumsohn Patent #2,006,999.

It will now be evident that the novel perforator will permit an ordinary typist, operating a standard keyboard in the same manner and as rapidly as in ordinary typewriting, to produce a perforated ribbon-like message of uncoded or ordinary reading matter. This is in contrast to the production of coded messages used in present day printing telegraphy. While standard keyboard manipulation is employed in printing telegraphy, it is necessary for the operator to know the particular code employed before the perforated tape issuing from the machine can be directly read or checked. Consequently, in the adaptation of this invention to traveling message signs or other ultimate purposes or systems, the tape forms a record which can be checked directly before transmission by persons who are unable to read special codes. Thus, in traveling message signs where the keyboard-perforator might be desirably located in a newspaper editorial room, the message flashed on a large outdoor sign may be proofread in plain English as

or even before transmitting, to preclude errors or to edit the message.

While ordinary printing telegraph keyboard perforators accomplish the object of perforating character elements in a single row or in relatively confined portions of the tape, it will be evident from the above description that the present invention provides a die block arrangement having an extensive group or field of punches embracing practically the entire character-area of the tape. This feature not only makes it possible to produce letters and figures—though nevertheless made up of perforations—conforming to any chosen alphabet or design but also, to a considerable extent, trade-marks, symbols, figures or other predetermined designs. This is highly desirable where my keyboard perforator is used in the transmission of messages in traveling message sign systems such as, for example, the one shown in the Nachumsohn Patent No. 2,006,999. In this respect the individual character area corresponding to the cluster of holes or punches in the die block represents a mosaic within which individual punches may be selected to form predetermined characters or designs.

It is to be noted that because my present invention combines all the letters and figures in a single character-wheel, it is possible through interchange of this single item to introduce different-shaped letters or characters without regard to or the disturbing of the individual keys or key-lever elements.

While I have described the invention along specific lines, various modifications other than the ones treated above may be made in the invention without departing from its principles as covered in the appended claims.

I claim:

1. In a keyboard-operated perforator, a punch-unit operable by pressure to perforate a tape, a hammer behind the punch unit, a rotatable disc between the hammer and the punch unit and adapted to be advanced to operate selected punches in the punch unit representing struck characters on the keyboard, a tubular shaft carrying the disc, an electrical hammer control carried by the disc at one end of the shaft, wiring for said control passing through the shaft to its other end, a rotary commutator carried by said other end and connecting with said wiring, a current feed, and brushes from the latter applied to said commutator.

2. The structure of claim 1, bearing means for the shaft, a power drive, a clutch freely mounted on the shaft and receiving motion from said drive, a yieldable element fixed on the shaft, and means carried by the shaft and urging the clutch in engagement with said element, said drive allowing for the longitudinal motion of the shaft on the advance of the disc.

3. A keyboard-operated perforator comprising a tape, means along the latter for periodically punching perforation units in the tape representing in similar form letters and characters struck on the keyboard, said units comprising single or laterally multiplied perforation columns corresponding to the range of said letters or characters between minimum and maximum widths, means for feeding the tape step by step for the spacing of perforation units according to maximum width during the intervals between the perforation punching operations, and other means to reduce the feed according to letters or characters of less than the maximum width, said

other means comprising a member pivoted horizontally at one end and extended at the other end with upward lugs in the depressing path of the keys relating to letters or characters of less than the maximum width, an arm included in the feeding means and taking a given stroke when the feed is for letters or characters of the maximum width, a horizontally and medially pivoted rocker element presenting an abutment at one end normally out of the path of said arm, an extension of said member beyond the pivot, and a link between the extension and the other end of said rocker element, the depression of any of said lugs by one of said keys acting through the member and the link to swing the rocker element with said abutment into the path of said arm, whereby to curtail the stroke thereof and shorten the feed accordingly.

4. The combination with a typewriter keyboard of a die block containing a group of punches arranged in block formation with punches selective to form any letter or character on the keyboard, a tape passed through the die block in the operative path of the punches, a hammer situated behind the punches, a selector disc between the hammer and the punches and formed with groups of perforations consecutively registerable with said punches on the lateral movement of the disc, each perforation group representing a keyboard letter or character and registering when opposite the punch group with punches not pertaining to such letter or character, means operative on the striking of any key to bring the corresponding perforation group opposite the punch group, and other means effective in such event to advance the hammer against the selector disc and cause the latter to operate such punches as pertain to said letter or character while the corresponding perforation group affords clearance for the remaining punches, the selector disc being rotatable and its perforation groups arranged in a circularly-spaced series, and said first means comprising a circular series of pins relating to the keyboard letters or characters, means to advance the pins when the corresponding letter or character keys are operated, an abutment carried by the selector disc in the path of any advanced pin, the position of the latter being such as to cause the disc to stop with the perforation group pertaining to the chosen letter or character opposite the punch group, said abutment being yieldable to an initial extent, a switch terminal carried by the abutment, a companion switch terminal carried by the selector disc and adapted to be contacted by the first switch terminal on the yielding of the abutment to close the switch, an electric circuit controlled by the switch, and a solenoid in said circuit and operative to advance said hammer on the closing of the switch.

5. A keyboard-operated perforator comprising a tape, a die block containing punches and means effective upon the manipulation of the individual keys of said keyboard for selecting predetermined punches corresponding to the keyboard characters, said means comprising a rotating character-defining disc having an index member rotating therewith and yieldably movable relative thereto, said disc normally rotatable in a plane immediately to the rear of said punches, a motor for rotating said disc through the medium of a clutch, an annular series of stop members each operable by a corresponding key and adapted to be moved thereby into the path of said index member to interrupt the rotation of said disc while permitting the motor to continue

rotation through the medium of said clutch, a perforating hammer located to the rear of said disc and in line with said punches, and means effective in response to said yieldable relative motion between the index member and the disc to move the hammer into engagement with said disc to shift the latter into a forward plane thereby engaging said punches to perforate the tape with the character selected, a tape-feed mechanism, an arm yieldably movable in one direction to store energy into a spring upon movement of the hammer into engagement with the disc and to permit said spring to operate said tape-feed mechanism upon movement of said hammer out of engagement with said disc.

6. A keyboard-operated perforator comprising a tape, a die block therefor containing punches, and means effective upon the manipulation of the individual keys of said keyboard and in selective registration with said punches for selecting predetermined groups of punches representing keyboard characters to perforate said tape accordingly, said means comprising a rotary spider bounded by an annular ring, the latter having groups of punch-selecting holes arranged in character formation, and the operation of any key effective to stop said spider and bring any group of said holes into registration with said punches, said ring having a pilot hole in radial registration with each of said groups of punch-selecting holes, a circular series of pins relating to said keys, means to advance any one of the pins when the corresponding one of said keys is operated, and an abutment carried by one of the spider arms in the path of any advanced pin, the position of the latter being such as to cause the spider to stop with the group of said punch-selecting holes pertaining to the chosen key opposite the group of punches, the advanced pin seating in the corresponding pilot hole to lock the ring in a position to hold such group of punch-selecting holes in registration with the group of punches.

7. A keyboard-operated perforator comprising a tape, means along the latter for periodically punching perforation units in the tape representing in similar form letters and characters struck on the keyboard, said units comprising single or laterally multiplied perforation columns corresponding to the range of said letters or characters between minimum and maximum widths, means for feeding the tape step by step for the spacing of perforation units according to maximum width during the intervals between the perforation punching operations, and other means to reduce the feed according to letters or characters of less than the maximum width, said maximum feeding means normally tending to feed the tape to maximum width, and said other means comprising a member effective to block the full motion of said maximum feeding means when a character of less than maximum width is struck.

8. The structure of claim 7, and a universal bar associated with the keyboard and operable only with the narrower characters thereof to actuate said member.

9. In a keyboard tape perforator a horizontal base supporting a set of character-defining keys, front and rear upstanding plates carried by said base, an annular series of stop plungers operable by said keys and movable forwardly of the frontal plate, a die block containing punches and supported forwardly of the frontal plate, a character-defining disc rotatably supported between the frontal plate and the die block, such disc

having character-defining elements adapted to directly engage the punches in the die block, and means disposed behind the frontal plate and effective upon the stopping of the disc by actuating of said stop plungers to cause the disc to advance forwardly and operate said punches.

10. The combination with a typewriter-like keyboard and a message tape, said keyboard including a plurality of separate character bearing keys; of means effective upon the successive manipulation of said keys for perforating directly readable alphabet letters and numerals successively in said tape, said means comprising a die block receiving said tape and common to all characters in said keyboard, a set of punches for said die block arranged in a plurality of rows, a continuously rotatable drive medium, a shaft operated by the same with allowance for the shaft to be stopped and shifted axially, a character-defining rigid disc fixedly centered on the shaft, said disc having separate sets of character-forming punch-actuating means arranged in a circular series about the center of the disc, each set corresponding to the character on one of said keys, means effective upon the operation of any key to stop the rotation of the shaft and disc in such position relative to said die block as to dispose the character-forming punch-actuating means corresponding to the character on said operated key opposite appropriate ones of said punches for the formation of said character, and means movable axially of the shaft to engage the disc with said punches following the stopping of the rotation of said disc as stated, said engagement causing the disc and its shaft to shift bodily as stated and act as a unit to operate the punches.

11. The combination with a typewriter-like keyboard, the latter including a plurality of separate character bearing keys, and a message tape; of means effective upon the successive manipu-

lation of said keys for perforating directly readable alphabet letters and numerals successively in said tape, said means comprising a die block receiving said tape and common to all characters in said keyboard, a set of punches for said die block arranged in a plurality of rows, bearing means, a rotary unitary character-defining member journaled in said bearing means, means effective upon the operation of any key to angularly position a selected portion of said rotary member opposite appropriate ones of said punches for the formation of a character corresponding to the character on said key and other means causing the member to move axially in said bearing means and operate said punches upon the striking of any key in predetermined character-formation corresponding to the key struck, whereby to cause the selected punches to perforate the tape accordingly.

IRVING NAXON.
